UNITED STATES PATENT OFFICE.

JOHN BERGSTEN, OF TAFT, CALIFORNIA, ASSIGNOR, BY MESNE ASSIGNMENTS, TO
STANDARD MACHINE COMPANY, A CORPORATION.

ELEVATOR.

Application filed May 31, 1922. Serial No. 564,780.

To all whom it may concern:

Be it known that I, JOHN BERGSTEN, a citizen of the United States, residing at Taft, in the county of Kern and State of California, have invented new and useful Improvements in Elevators, of which the following is a specification.

This invention relates to elevators, and particularly to well elevators for handling casings, tubings, sucker rods and other elements and apparatus involved in the drilling, operation and maintenance of oil and other wells; and it has for its object the provision of an improved elevator of the general characteristics above designated, which will be superior in point of relative inexpensiveness and simplicity of construction, durability and positiveness and efficiency in operation, resistance to the stresses incident to use in operation, and general serviceability.

The invention contemplates an elevator which is so formed as to receive and hold tubings, whether they be of the plain or up-set style. In this particular the elevator is designed for service within the general field above defined and the elevator is universal in its application, obviating the necessity of providing different forms of elevators for different styles of tubing. Other details of the invention reside in the specific form of latch mechanism, as well as the ease and facility with which the elevator may be used.

With the above initially stated objects in view, the invention consists in the novel provision, construction, combination, association, relative arrangement and formation of parts, members and features, all as hereinafter described, shown in the drawing, and finally pointed out in claims.

In the drawing:

Figure 1 is a fragmentary elevation of the improved elevator engaging tubing and supporting the same;

Figure 2 is a view similar to Figure 1, said view having a part thereof in cross section and taken on the line 2-2 of Figure 3, and looking in the direction of the appended arrows;

Figure 3 is a cross sectional view of the elevator taken on the line 3-3 of Figure 1, and looking in the direction of the appended arrows;

Figure 4 is a view similar to Figure 3,

and showing an open position of the latch member;

Figure 5 is a fragmentary view of the said device taken on the line 5-5 of Figure 3, and looking in the direction of the appended arrows; and

Figure 6 is a fragmentary view of certain features of the invention, taken on the line 6-6 of Figure 3, and looking in the direction of the appended arrows.

Corresponding parts in all the figures are designated by the same reference characters.

Referring with particularity to the drawing, the improved elevator is designated in its entirety by A, of which a is the bail or suspension means, and b and c the body and gate members, respectively, or considered broadly the clamping and holding means. The body member b is formed with a slot 1 giving a bifurcated appearance to the body, that is to say, two spaced arm members 2 and 3 and an inter-connecting portion 4. The body b is provided with two trunnions 5 and 6 and the bail, as is customary, is provided with eye members 7 and 8 adapted to engage said trunnions, and whereby the body and gate may be carried, or swiveled if desired. Both arms 2 and 3 of the body b, as well as the inter-connecting portion 4 between the arms is recessed as shown at 9, 10 and 11, and a portion of the gate member 80 c is confined within the recesses 9 and 10 when said gate is in the position as shown in Figure 3. In particular the arm 2 is relieved at the part marked 12, whereby the gate member may swing to an open position, as shown in Figure 4, ready to receive tubing 13 or other elements and apparatus involved in the drilling. The opposite arm 3 is formed to receive a locking means 14 operated by means of a handle 15. The 95 gate c will be described first and then its connection with the body, and the operation will follow; in this particular, referring to Figure 1, it will be seen that the gate member is so formed as to have a curved portion 100 or arm 16 and an inter-connecting part or arm 17, the curved portion 16 being normally received within the recess 10 when the gate is in the closed position shown in Figure 3 with the part 17 of a size corresponding to the depth or thickness of the body member b. The part 17 is provided 105 with flanges 18 and 19 at each edge thereof,

which flanges overlap the body 3 when the gate is in closed position. To permit this overlapping, the body at the extremity of the arm portion 3 is grooved as shown at 5 20 and 21, and the tongue, as 22, formed by the grooves 20 and 21 in the body is received between the flange extensions of the gate c. It will thus be seen that when the gate is in the closed position illustrated in 10 Figures 1 and 3 the gate may aid in carrying the weight of the work imposed upon the elevator. To permit the gate to swing open or closed, the said gate is pivoted to the said body as by means of a pin 23 passing through a part of the body and through an opening in the gate. The curved arm portion 16 of the gate c lies in advance of the arm 17 and is the first to contact with any work, with the part 17 following the 15 work and closing behind it. It will be seen that the relieved portions 20 and 21 forming the tongue 22 are in reality abutments upon which the flanges 18 and 19 rest when the gate is in closed position. The curved arm 20 16 aids in sustaining any work by being within the recess 10 of the body, and the pin 23 as a consequence carries very little weight. To maintain the gate c in closed position I provide the locking means 25 14 which includes a tubular member 24 closed at one end and adapted to fit within the recessed portion 9 of the arm 3. A countersunk recess 25 in the arm 3 is adapted to receive a plate 26 carrying a projection 27. Within the tubular member 24 is confined a coil spring 28, the projection 27 being received within the coils of the spring for aid in guiding movement of the spring and the tubular member 24, as will 30 35 be seen in Figure 3. In order to retain the plate 26 in position within the counter-sunk recess, the arm 3 is counter-sunk at both ends as at 29 and 30, thus forming two lug members 31 and 32, as between the recesses 40 45 25, 29 and 30, there being a bore extending transversely through the lugs 31 and 32, which bore is adapted to receive a retaining means for holding the plate member 26 in position within the recess 24, said means in 50 55 the showing of Figure 6 being a cotter pin 33. The tubular member 24 is formed with a protuberance or lug 34 and the pivoted lever arm or releasing trigger 15 is bifurcated as at 35, the lug 34 being received between the two members forming said bifurcation. The arm or trigger 15 is pivoted as at 36 within the recess 9 to the arm 3, and the free end 37 of said arm is curved to form a finger-piece. Thus, upon grasping 60 65 or otherwise contacting with the finger-piece, it is possible to move the latch back and forth, whereby it may be either closed or opened to engage the gate or release the gate.

65 The gate and the body are so formed that

they may accommodate either plain or upset tubing, and in this particular, reference being had to Figures 2 and 5, it is to be noted that one face of said gate and body is recessed as at 38, whereby the upset portion of the tubing may be accommodated. The opposite side of the gate does not carry a recess, and tubing carrying collars may be accommodated by said side, as illustrated in Figure 1. This construction makes this 70 75 elevator universal in its adaptation and use, overcoming the necessity of providing different forms and shapes of elevators for different requirements of use and service.

In operation it is only necessary to rotate 80 the body with its gate, whereby the same may accommodate either the plain or upset tubing and then close the gate, the latch mechanism automatically being forced into position to lock the gate closed. A releasing of the trigger will force the latch back and allow the gate to be swung open. It will thus be seen that I have provided a structure that is simple, economical in manufacture, and which will perform the work 85 90 required of it in a facile manner.

It is obvious that various changes and modifications may be made in departure from the particular showing and description, all of said changes and modifications 95 being made within a fair interpretation of the claims.

Having thus disclosed my invention, I claim and desire to secure by Letters Patent:

1. In an elevator, a body having spaced 100 arms providing a recess adapted to accommodate work, a gate having spaced arm portions mounted in a recess in the body portion and adapted to be swung to extend the arms across said recess in the body portion, the work being adapted likewise to be accommodated between said arms, whereby one of said arms leads the work and the other of said arms follows the work upon its accommodation within the recess in said body; said body and said following arm having portions which jointly receive the weight of the load when said gate is in closed position; means being provided for maintaining said gate in such closed position; means likewise being provided for freeing the gate from such closed position. 110 115

2. In an elevator, a body having spaced arms providing a recess adapted to accommodate work, a gate having spaced arm portions mounted in a recess in the body portion and adapted to be swung to extend the arms across said recess in the body portion, the work being adapted likewise to be accommodated between said arms, whereby one of said arms leads the work and the other of said arms follows the work upon its accommodation within the recess in said body; said body and said following arm having portions which jointly receive the 120 125 130

- weight of the load when said gate is in closed position; means being provided for maintaining said gate in such closed position; means likewise being provided for freeing the gate from such closed position; said means comprising a spring-actuated latch cooperating with the following arm of said gate, and a releasing trigger for retracting said latch.
3. In an elevator, a body having spaced arms providing a recess adapted to accommodate work, a gate having spaced arm portions mounted in a recess in the body portion and adapted to be swung to extend the arms across said recess in the body portion, the work being adapted likewise to be accommodated between said arms, whereby one of said arms leads the work and the other of said arms follows the work upon its accommodation within the recess in said body; said body and said following arm having portions which jointly receive the weight of the load when said gate is in closed position; means being provided for maintaining said gate in such closed position; means likewise being provided for freeing the gate from such closed position; said means comprising a spring-actuated latch cooperating with the following arm of said gate, and a releasing trigger for retracting said latch; said latch
- and said releasing trigger being accommodated in said recess in said body.
4. In an elevator, a body having spaced arms providing a recess adapted to accommodate work, a gate having spaced arm portions mounted in a recess in the body portion and adapted to be swung to extend the arms across said recess in the body portion, the work being adapted likewise to be accommodated between said arms, whereby one of said arms leads the work and the other of said arms follows the work upon its accommodation within the recess in said body; said body and said following arm having portions which jointly receive the weight of the load when said gate is in closed position; said elevator being reversibly mounted, and said body having upper and lower abutments; said gate having top and bottom flanges cooperating respectively with said abutments by which weight of the work may be transmitted to the respective abutment.

In testimony whereof, I have signed my name to this specification in the presence of two subscribing witnesses.

JOHN BERGSTEN.
